WASTE AND DUST MOP CLEANING CAN

Einar W. Nielsen, Maplewood, N. J.

Application November 25, 1941, Serial No. 420,839

7 Claims. (Cl. 15—15)

This invention relates to a can or receptacle which can be used for a plurality of purposes such as a can for receiving paper or waste around the house or apartment, and for cleaning a dust mop thereinto.

It is the usual practice today for a housekeeper, after dusting up a room, in cleaning the dust mop, to lean out of the window and beat the dust mop against the side of the house.

It is the object of my invention to avoid these old methods of cleaning a dust mop and to provide a much easier and cleaner way of doing it. To this end I have conceived an arrangement of a receptacle or can which can be used for two purposes: first, it may be used as a waste receptacle or can for paper and other things that find their way into a waste can around the house; and, second, as a means for cleaning the dust mop without being obliged to open the window and shake it therefrom, as this process is hard in the summertime because of the screens on the window which, if pushed out too far, will usually unhook and may drop on someone's head; and objectionable in the winter-time as it cools off the house or apartment.

While attaining the principal object of my invention, other ancillary objects will appear from the following description taken in connection with the drawing wherein:

Figure 1 is a side elevation of one form of receptacle or can.

Figure 2 is a top plan view of Figure 1.

Figure 3 is a sectional view on the line 3—3 of Figure 2, but showing a mop in cleaning position, together with a vacuum cleaner in position to take up the dust removed from the mop.

Figure 4 is a plan view of a modified form of construction.

Figure 5 is a section on the line 5—5 of Figure 4.

In Figures 1, 2 and 3, the can or receptacle is made of any satisfactory material and can be made in any desired shape, either oval or round, the oval shape shown in Figure 2 being one very good form of making the can. Along one side of the can there is an opening 2 leading into a recess 3 which may be formed directly in the side of the can or built thereinto by way of a partition 4, thereby separating the recess 3 from the interior portion of the can. The lower part of the partition 4 or bottom of the recess 3 has a platform 5 which is adapted to receive the nozzle or suction portion 6 of a vacuum cleaner 7. The vacuum cleaner suction portion 6 is readily moved into and out of the recess 3 and onto

the platform 5. The platform 5 is provided with an elongated slot 8 adapted to cooperate with the opening in the nozzle 6 of the vacuum cleaner.

Normally, the opening 2 and recess 3 are covered by a circular cover or collar 9 which is provided with a pair of handles 10 and 11 for raising and lowering the collar 9 over the opening 2. The handles 10 and 11 are preferably resilient with their ends resting in openings 12 and 13 on opposite portions of the collar, in engagement with the walls of the can 1, thereby holding the collar in its raised position when it is desired to clean a mop 14 which is inserted in the top of the can after the vacuum cleaner has been positioned as illustrated in Figure 3 and the current turned onto the motor of the vacuum cleaner.

When the mop is shaken within the can, the dust is drawn downwardly past the partition 4 and through the slot 8 in the platform 5 and into the vacuum cleaner. After the mop-cleaning operation has been performed, the vacuum cleaner is removed and the collar 9 is moved to closed position as shown in Figure 1, then the can can be used as a receptacle for paper and other waste materials.

In the form shown in Figures 4 and 5, the can is a little differently shaped and the platform 5 extends clear across the bottom of the can and has, in addition to the opening 8, another opening 15. In addition, the interior surface of the collar may have one or more spring members 16 positioned in a recess in the collar and in engagement with the wall of the receptacle 1.

In the different forms shown, it is preferable to provide the upper end of the can with a ring 17 to prevent the collar from being accidentally withdrawn from the can. Likewise, the bottom of the can is provided with a flange 18 for the collar to engage when in closed position.

While I have shown two general forms or outlines of the can, the shape may be round, rectangular or any other desired form, but preferably the form should be one which is best adapted for the use of a vacuum cleaner. Using the can for the dual purpose as described, provides a much easier, and more sanitary means of cleaning dust mops.

It will be noticed, by reference to the drawing, that the can or receptacle may be used as a waste-paper can without the use of the collar 9 for the reason that the usual kind of waste paper thrown into the receptacle will not find its way out of the relatively narrow slot 8 in the partition separating the interior part of the can from

the recess 3. Furthermore, by setting the can, with the recess 3 toward the wall, the recess will be concealed from view and the can will have the appearance of having a continuous surface. The use of the collar is merely to cover the recess 3 and absolutely prevent any fine pieces of paper or waste from getting out of the interior of the can through the recess 3, and also to make the can look more like the usual type of waste basket or can, therefore not requiring that the can be placed in a certain position with respect to the wall of the room.

What I claim is:

1. A self-supporting, non-collapsible can for the dual purpose of receiving waste material and for use in cleaning a dust mop, the can having an outside recess permanently formed by an inwardly projecting portion of the wall of the can to receive the suction portion of a vacuum cleaner, the recess having a platform spaced a short distance from the regular can bottom, the platform having at least one slot therein in alignment with the suction slot in the vacuum cleaner when it is inserted into the recess, and a collar normally fitting over the recess to allow the can to be used as a regular waste can or basket, the collar being bodily vertically movable to uncover said recess so the can can be used for cleaning a dust mop in the manner described.

2. A self-supporting, non-collapsible can for the dual purpose of receiving waste material and for use in cleaning a dust mop, the can having an outside recess permanently formed by an inwardly projecting portion of the wall of the can to receive the suction portion of a vacuum cleaner, the recess having a platform spaced a short distance from the regular can bottom, the platform having at least one slot therein in alignment with the suction slot in the vacuum cleaner when it is inserted into the recess, and a ring-type collar normally fitting around the can over the recess, with means for bodily raising the collar and holding it in raised position to allow the vacuum cleaner to be inserted into said recess so a mop may be shaken within the can.

3. A self-supporting, non-collapsible can for the dual purpose of receiving waste material and for use in cleaning a dust mop, the can having an outside recess permanently formed by an inwardly projecting portion of the wall of the can projecting within the can to receive the suction portion of a vacuum cleaner, the can having a platform extending across the interior of the can and spaced a short distance from the bottom of the can and having oppositely disposed slots, one of which is positioned to cooperate with the slot in the vacuum cleaner nozzle, the inner wall of the recess intercepting the platform between the slots therein, and a collar normally fitting over the recess to allow the can to be used as a regular waste can or basket, the collar being bodily ver-

tically movable to uncover said recess so the can can be used for cleaning a dust mop in the manner described.

4. A self-supporting, non-collapsible can for the dual purpose of receiving waste material and for use in cleaning a dust mop, the can having an outside recess to receive the suction portion of a vacuum cleaner, the recess having a platform spaced a short distance from the regular can bottom, the platform having at least one slot therein in alignment with the suction slot in the vacuum cleaner when it is inserted into the recess, and a collar normally fitting around the lower part of the can over the recess to allow the can to be used as a waste-paper can, the collar being bodily vertically movable to uncover the recess for the reception of a vacuum cleaner nozzle portion to allow the can to be used as a dust mop cleaner, and means to hold the collar in raised position.

5. A self-supporting, non-collapsible can for the dual purpose of receiving waste material and for use in cleaning a dust mop, the can having an outside recess permanently formed by an inwardly projecting portion of the wall of the can to receive the suction portion of a vacuum cleaner, the recess having a platform spaced a short distance from the regular can bottom, the platform having at least one slot therein in alignment with the suction slot in the vacuum cleaner when it is inserted into the recess, and a collar normally fitting over the recess to allow the can to be used as a regular waste can or basket, the collar being bodily vertically movable to uncover said recess so the can can be used for cleaning a dust mop in the manner described.

6. A household utility waste-and-mop-cleaning can, the can having an interior portion for receiving waste or a dust mop requiring cleaning, and an exterior portion formed by an inwardly projecting part of the can wall for receiving the suction end of a vacuum cleaner, the two portions being divided in part by bottom wall means having at least one communicating slot joining the two portions and located for cooperative relation with the vacuum cleaner pick-up slot, and a collar on the can bodily movable to convert the can to the uses specified.

7. A household utility waste-and-mop-cleaning can, the can having an interior portion for receiving waste or a dust mop requiring cleaning, the can having an upright wall with an opening formed therein, a wall positioned wholly within and extending along the interior portion of the can adjacent said opening to define a nozzle-receiving chamber, the lower part of the projecting wall being spaced from the bottom of the can and having at least one communicating slot joining the said interior portion and said chamber, and located for cooperative relationship with a vacuum cleaner pickup slot.
